UNITED STATES PATENT OFFICE

ALBERT H. TAYLOR, OF WASHINGTON, DISTRICT OF COLUMBIA, ASSIGNOR TO WIRED RADIO, INC., OF NEW YORK, N. Y., A CORPORATION OF DELAWARE

MULTIPLE-CHANNEL COMMUNICATION SYSTEM

Application filed May 14, 1925. Serial No. 30,252.

My invention relates broadly to high frequency signaling systems, and more particularly to a multiple channel transmission system.

5 One of the objects of my invention is to provide a circuit arrangement for high frequency signal transmission whereby a plurality of independent signaling circuits may be employed for independent modulation to impress signaling currents upon a common amplification system from which the independent sets of signals may be conveyed to a carrier wave line wire system or to an antenna ground radiating system.

15 Another object of my invention is to provide a circuit arrangement for each of a plurality of independent high frequency signaling systems for maintaining said systems at a constant operating frequency in such manner that the systems are prevented from interacting one upon another for the multiple operation of several communication channels over the same line wire system or by radiation from the same antenna ground system.

25 Still another object of my invention is to provide a signaling system having a plurality of channels for conducting communication without mutual interference over the same carrier wave circuit or radiation circuit in which quartz crystals of certain definite frequencies are arranged in circuit with the transmission channels for independently controlling the frequency of each of the channels for preventing mutual reaction of one channel upon another in the process of simultaneous operation of the circuits.

35 Still another object of my invention is to provide independent crystal control circuits for a plurality of transmitting circuits arranged to deliver signaling energy to the same carrier wave line wire system or to the same antenna ground system in which the crystals are ground to definite frequencies and connected in circuit with independent oscillators for maintaining the oscillators at the signaling frequency free of mutual inter-action.

45 A further object of my invention is to provide crystal control circuits for a multiple channel communication system where independent electron tube oscillators may be

55 maintained at different frequencies separated from each other by only a small percentage in frequency, while the power supply for the electron tubes may be derived from a common source and the oscillations impressed upon a common signaling circuit without inter-action between the oscillations.

60 When my invention is employed in radio transmission, I find that the system is particularly adapted to minimize fading effects 60 by transmitting the same message on two simultaneous emitted frequencies. These separate frequencies seldom fade out simultaneously at the receiving end. The use of 65 two receivers and various means for combining the outputs of the two receivers, as, for instance, as set forth in my Letters Patent 1,376,051, dated April 26, 1921, putting the output of one through the right-hand ear phone and the output of the other through 70 the left-hand ear phone further insures against loss of signal by fading. Since it is well known that a very small change in frequency is sufficient to alter the time and the amount of fading, such a combination gives 75 considerable protection against loss of a portion of the message by fading. When used for multiple channel communication for independent messages, traffic may be routed through both of the transmitting circuits 80 radiating independent messages simultaneously from the same antenna system. The antenna systems may be given particular directional characteristics in such manner that, with the transmitting station located at the 85 Navy Department, Washington, D. C., one channel may be in direct communication with Europe, while another channel is in simultaneous communication with the Philippines. 90

95 My invention makes use of the constant frequency characteristics of the piezo electric effects possessed by quartz crystals. I have illustrated my invention as applied to two-channel communication system where a pair of electron tubes is arranged in a bilateral circuit for alternating current supply on the anodes or plates with the cathodes or filaments lighted or heated from an alternating current power supply. Two independent quartz crystals are prepared by grinding the crystals 100

to two different frequencies and the crystals connected around the input circuits of each of the oscillators for controlling the frequency thereof. The oscillators operate in alternation, one on one lobe of the alternating current power supply and the other on the opposite lobe of the alternating current power supply. The outputs for the several tubes are supplied to a common utilization circuit in a manner which will be more fully described hereinafter and simultaneous but independent communication maintained by modulation of the oscillator circuits.

My invention will be more clearly understood from the specification hereinafter following by reference to the accompanying drawing which diagrammatically illustrates a two-channel communication system embodying the principles of my invention. The circuit arrangement includes electron tubes 1 and 2 each having a cathode 1^a and 2^a, a plate or anode 1^b and 2^b, and a control electrode or grid 1^c and 2^c. The high potential source for the electron tubes is derived from a common power supply system. There are two quartz crystals provided marked QC¹ and QC², one controlling the frequency of the left-hand tube 1 and the other that of the right-hand tube 2. Separate sensitizing chokes 3 and 4 are each connected in circuit with the quartz crystals QC¹ and QC² and around the input circuit of the tubes 1 and 2. The sensitizing choke 3 has a free wavelength characteristic somewhat shorter than the frequency to which the crystal QC¹ is ground. Similarly, the sensitizing choke 4 has a free wavelength characteristic somewhat shorter than the frequency for which the crystal QC² is ground. Each choke is placed in series with its own corresponding crystal. The anode or plate supply for the tubes is obtained from any suitable source through line system 5 and an anode supply transformer 6 having primary winding 7 and secondary winding 8. It is well to use an alternating current supply of frequencies sufficiently high to give a pleasing tone to the received signals. It has been found that frequencies between 240 and 600 cycles are satisfactory for this purpose, although experiments have been made with frequencies as low as 25 cycles. The anode 1^b of tube 1 has radio frequency choke 9 in series therewith and signaling key 10 is connected in the plate circuit and with one end of the secondary 8. The anode 2^b of the electron tube oscillator 2 includes radio frequency choke coil 11 in circuit therewith and a signaling key 12 is series connected into circuit with the opposite end of the secondary winding 6. At the midpoint 14 in the secondary winding 8 a connection is taken to the shield 15 which entirely screens the oscillator and forms a ground connection for the several circuits of the oscillator. The output of the several

tubes is delivered to a common circuit including inductance 16 and variable capacity 17. The circuits are adjusted for oscillation by phase adjustment in the plate circuits under control of the variable condenser 17 by reason of its parallel relationship to the common plate circuit inductance 16. It is only necessary that the two quartz crystals do not differ by more than a small percentage in frequency in order to have a single adjustment of the condenser 17 suitable for the production of oscillations of different frequencies; one in the right-hand tube 2 and the other in the left-hand tube 1, but both pass through the common plate coil system. Suppose, for example, the circuit is operated in the neighborhood of 4000 kcs.—the crystals would then differ by as much as 10 kc. from each other and only have a difference in frequency of one-fourth of one percent. This is too small from a percentage point of view to throw any of the circuits sensibly out of tune, and therefore these two frequencies are both produced in the common plate coil system with a single setting of 17, which can be so adjusted as to bring the oscillations of the two frequencies through with substantially the same energy or, if desired, the emphasis can be put on one or the other of the two frequencies. It is understood of course that various forms of coupling may be used in this plate output circuit and that I do not intend the invention to be limited to the particular arrangement shown.

Any combination of plate circuit inductances may be used for delivering the independent oscillations to the signaling systems. Where coupled circuits are used however the coupling should be quite close in order that the rotation of the condenser 17 will adequately control the phase of the current in the plate circuit and therefore establish the correct phase relations for the development of the oscillations of the crystals. It is advisable to use a certain amount of shielding as illustrated, but it is not absolutely necessary.

The cathodes 1^a and 2^a are each heated from transformer 18 having primary winding 19 thereof supplied from the line wire system and secondary winding 20 coupled thereto. Cathode 2^a is connected across the ends of the secondary winding 20 while a midpoint 21 is connected to the shield or ground 15 through conductor 22. The output circuits 16 and 17 may deliver signaling energy to the input circuit of a suitable power amplifier 23 from which the energy may be impressed upon a carrier wave line wire system or the antenna radiating system represented at 24 and 25. It is advisable to use a certain amount of negative "C" voltage in connection with crystal control oscillators. These negative "C" voltages can be obtained from the taps on the plate circuit transformer 6 with the resistances marked 26 and 130

- 27 in series with these negative "C" taps on the transformer winding 8 which prevent a rush of current in the tubes 1 and 2 when the plate voltage and grid voltages reverse. 5 During that half-cycle when a tube is non-oscillating, with this precaution it is perfectly possible to derive negative "C" voltage from taps on the plate circuit transformer.
- 10 Resistance 27 is connected in series with radio frequency inductance 28 and supplies the proper bias potential to the grid electrode 1° of the tube 1. The radio frequency choke coil 29 is connected in series with resistance 15 26 and supplies the proper grid bias potential to the grid electrode 2°. Each wave is modulated at the supply frequency. In other words, it consists of the carrier wave with the usual side bands and can be received with 20 either oscillating or non-oscillating detector in the usual manner. If crystal control were not used the point must be emphasized that it would not be possible to receive a smooth, clean-cut signal unless the two crystals were 25 ground identical and only one wave emitted, because the sequence of phase would be broken and the action of the heterodyne or autodyne reception would be to give a very rough received tone like an oscillating circuit receiving a spark signal. But the damping of 30 the crystals is so slight that feeble oscillations will hang over in the crystal from cycle to cycle, thus starting off consecutive oscillation groups as first one plate, then the other 35 becomes positive in their proper sequences of phases. This is a very important point because it permits of a far superior type of reception with oscillating detector. There is also a limit as regards the frequencies of the 40 two waves emitted where it is not possible to key at telegraphic speed on account of the slowness of response of the crystal. Experiments have been made between 3000 and 4000 45 kecs. however which show that at these frequencies satisfactory keying as high as twenty-five words per minute is readily possible and probably at considerably higher frequencies. These two frequencies are not given off simultaneously, but in alternating groups, the 50 sequence of phase in each group of frequencies being maintained intact due to the property of the respective crystals, thus permitting smooth reception with heterodyne or autodyne. No additional complications are 55 necessary in the power amplifier and antenna circuits because these two emitted frequencies differ by so little in percentage tuning, that they will both readily pass through the power amplifier system and into the antenna.
- 60 I provide condensers 30, 31, 32, 33, 34 and 35 at the points in the electron tube circuits, as indicated, for by passing radio frequency currents and improving the efficiency of the system.
- 65 It will be observed that, ordinarily, when it is attempted to operate a plurality of oscillators anywhere in proximity of each other that the difficulty encountered is the tendency of the tubes to pull each other into step, which by the inter-action of the circuits entirely 70 destroys the multiple functioning of the system. By my arrangement of quartz crystal control these several circuits are maintained absolutely independent in their operation even when separated at only a small percentage in frequency. 75
- While I have described my invention in certain particular embodiments, I desire that it be understood that modifications may be made and that I intend no limitations upon the invention other than are imposed by the scope of the appended claims. 80
- What I claim and desire to secure by Letters Patent of the United States is as follows:—
1. A multiple channel communication system comprising in combination a plurality of high frequency generators, a common energy supply system for alternately energizing said generators, a common energy utilization circuit connected with said generators, independent mechanically vibratile devices connected with each of said generators for maintaining said generators at a constant operating frequency, whereby inter-action between said generators is prevented, and means for independently controlling each of said generators for producing telegraphic signals in said common energy utilization circuit. 85
2. A multiple channel communication system comprising in combination a plurality of high frequency energy generating circuits, a common source of power supply for alternately energizing said circuits, a common utilization circuit for the high frequency currents generated in said circuit, independent piezo electric devices each ground to different selected frequencies connected in each of said circuits for maintaining said circuits at separated operating constant frequencies, and means for controlling each of said circuits independently for impressing signaling currents of different frequencies upon said common utilization circuit. 100
3. A multiple channel communication system comprising in combination a pair of high frequency generators, a source of alternating current power supply for alternately energizing each of said generators, a common energy utilization circuit connected with said generators, and piezo electric devices each ground to a different operating frequency connected in shunt with each of said generators for maintaining said generators at a constant operating frequency separated by a small percentage in frequency, whereby slightly separated signaling frequencies may be impressed upon said common energy utilization circuit. 115
4. A multiple channel communication sys- 130

- tem comprising in combination a pair of generators of high frequency current, a common power supply system for alternately energizing said generators, a common energy utilization circuit connected with said generators, and independent piezo electric crystal elements each ground to different operating frequencies connected with each of said generators and between said power supply circuit 5 connected in said output circuit, and constant frequency determining means comprising mechanical vibratile elements connected in the input circuits of each of said tubes for independently controlling the frequency of oscillations developed by said tubes, whereby signaling currents of separated frequencies are impressed upon said energy utilization circuit. 70

10 8. A multiple channel communication system comprising in combination a pair of electron tubes, each having grid, filament and plate electrodes, an input circuit for each of said tubes including the grid and filament electrodes of said tubes, an output circuit for each of said tubes including the plate and filament electrodes of said tubes, a common energy supply system for said filaments, an energy supply system for alternately energizing the plate electrodes of each of said electron tubes, a common energy utilization circuit connected in said output circuit, and a quartz crystal circuit connected in shunt with each of said input circuits for independently controlling the frequency of each of said tubes, one of said quartz crystal circuits differing in frequency from the other of said quartz crystal circuits whereby signaling currents of separated frequencies are impressed upon said common energy utilization circuit. 75

15 9. A multiple channel communication system comprising in combination a pair of electron tube oscillators, each of said tubes including a grid, filament and plate electrode, input circuits connected between the grid and filament of each of said tubes, and output circuits connected between the plate and filaments of each of said tubes, a common power supply means for alternately energizing said 20 circuits, a common energy utilization circuit connected in said output circuits, and piezo electric crystal elements each ground to different operating frequencies connected in the input circuits of each of said tubes for maintaining the frequency of the oscillations delivered to said energy utilization circuit at slightly separated frequencies for producing independent signaling currents in said energy utilization circuit. 85

25 10. A multiple channel communication system comprising in combination a pair of electron tubes, each having grid, filament and plate electrodes, an input circuit for each of said tubes including the grid and filament electrodes of said tubes, an output circuit for each of said tubes including the plate and filament electrodes of said tubes, a common energy supply system for said filaments, an energy supply system for alternately energizing the plate electrodes of each of said tubes, a common energy utilization circuit connected in said output circuit, and a device for sustaining constant frequency oscillations connected in the input circuits of each of said tubes for independently controlling the generation of a constant frequency by said tubes whereby signal currents separated from each other in frequency may be produced in said energy utilization circuit. 90

30 11. A multiple channel communication system comprising in combination a pair of electron tubes, each having grid, filament and plate electrodes, an input circuit for each of said tubes including the grid and filament electrodes of said tubes, an output circuit for each of said tubes including the plate and filament electrodes of said tubes, a common energy supply system for said filaments, an energy supply system for alternately energizing the plate electrodes of each of said tubes, a common energy utilization circuit connected in said output circuit, and a quartz crystal circuit connected in shunt with each of said input circuits and an element connected in series 95

35 12. A multiple channel communication system comprising in combination a pair of electron tubes, each having grid, filament and plate electrodes, an input circuit for each of said tubes including the grid and filament electrodes of said tubes, an output circuit for each of said tubes including the plate and filament electrodes of said tubes, a common energy supply system for said filaments, an energy supply system for alternately energizing the plate electrodes of each of said tubes, a common energy utilization circuit connected in said output circuit, and a device for sustaining constant frequency oscillations connected in the input circuits of each of said tubes for independently controlling the generation of a constant frequency by said tubes whereby signal currents separated from each other in frequency may be produced in said energy utilization circuit. 100

40 13. A multiple channel communication system comprising in combination a pair of electron tubes, each having grid, filament and plate electrodes, an input circuit for each of said tubes including the grid and filament electrodes of said tubes, an output circuit for each of said tubes including the plate and filament electrodes of said tubes, a common energy supply system for said filaments, an energy supply system for alternately energizing the plate electrodes of each of said tubes, a common energy utilization circuit connected in said output circuit, and a quartz crystal circuit connected in shunt with each of said input circuits and an element connected in series 105

45 14. A multiple channel communication system comprising in combination a pair of electron tubes, each having grid, filament and plate electrodes, an input circuit for each of said tubes including the grid and filament electrodes of said tubes, an output circuit for each of said tubes including the plate and filament electrodes of said tubes, a common energy supply system for said filaments, an energy supply system for alternately energizing the plate electrodes of each of said tubes, a common energy utilization circuit connected in said output circuit, and a device for sustaining constant frequency oscillations connected in the input circuits of each of said tubes for independently controlling the generation of a constant frequency by said tubes whereby signal currents separated from each other in frequency may be produced in said energy utilization circuit. 110

50 15. A multiple channel communication system comprising in combination a pair of electron tubes, each having grid, filament and plate electrodes, an input circuit for each of said tubes including the grid and filament electrodes of said tubes, an output circuit for each of said tubes including the plate and filament electrodes of said tubes, a common energy supply system for said filaments, an energy supply system for alternately energizing the plate electrodes of each of said tubes, a common energy utilization circuit connected in said output circuit, and a quartz crystal circuit connected in shunt with each of said input circuits and an element connected in series 115

55 16. A multiple channel communication system comprising in combination a pair of electron tubes, each having grid, filament and plate electrodes, an input circuit for each of said tubes including the grid and filament electrodes of said tubes, an output circuit for each of said tubes including the plate and filament electrodes of said tubes, a common energy supply system for said filaments, an energy supply system for alternately energizing the plate electrodes of each of said tubes, a common energy utilization circuit connected in said output circuit, and a quartz crystal circuit connected in shunt with each of said input circuits and an element connected in series 120

60 17. A multiple channel communication system comprising in combination a pair of electron tubes, each having grid, filament and plate electrodes, an input circuit for each of said tubes including the grid and filament electrodes of said tubes, an output circuit for each of said tubes including the plate and filament electrodes of said tubes, a common energy supply system for said filaments, an energy supply system for alternately energizing the plate electrodes of each of said tubes, a common energy utilization circuit connected in said output circuit, and a quartz crystal circuit connected in shunt with each of said input circuits and an element connected in series 125

65 18. A multiple channel communication system comprising in combination a pair of electron tubes, each having grid, filament and plate electrodes, an input circuit for each of said tubes including the grid and filament electrodes of said tubes, an output circuit for each of said tubes including the plate and filament electrodes of said tubes, a common energy supply system for said filaments, an energy supply system for alternately energizing the plate electrodes of each of said tubes, a common energy utilization circuit connected in said output circuit, and a quartz crystal circuit connected in shunt with each of said input circuits and an element connected in series 130

with each of said crystals and having a free wave-length less than the frequency of the crystal with which it is connected for independently controlling the frequency of each of said tubes, whereby signaling currents of separated frequencies are impressed upon said common energy utilization circuit.
